[57] CLAIM

The ornamental design for a broom and vacuum cleaner or similar article, as shown and described.

DESCRIPTION

FIG. 1 is a perspective view of a combined broom and vacuum cleaner or similar article showing our new design;

FIG. 2 is a side elevational view thereof, the opposite side, with the exception of the on/off switch near the top of the broom handle, being a mirror image; and FIG. 3 is a front elevational view thereof.

The electric cord is partially shown in FIGS. 2 and 3 for ease of illustration only.

FIG. 1

FIG. 2

FIG. 3
